UNITED STATES PATENT OFFICE

WILLIAM AUGUST MOELLER, OF LOS ANGELES, CALIFORNIA

FOLDING BED

Application filed April 23, 1929. Serial No. 357,594.

This invention has to do with a folding bed, and it is a general object of the invention to provide a simple, effective and improved folding bed of the type commonly known as a davenport or day bed.

It is a primary object of this invention to provide a folding bed that occupies a minimum amount of space.

It is another object of the invention to provide a folding bed of the davenport type in which the back is automatically operated to a position clear of the other parts upon the device being operated to the extended position.

Another object of the invention is to provide a simple, improved, lever mechanism for a bed construction of the character mentioned.

It is another object of my present invention to provide a davenport type of folding bed in which the back portion is shiftable and is counterbalanced to operate freely.

It is another object of my invention to provide a davenport type of folding bed which is of simple construction and which is convenient and easy to operate.

A further object of my invention is to provide a davenport type of folding bed in which the back portion is adapted to be moved to an up position out of engagement with the seat portion and to remain in such position until deliberately operated.

The various objects and features of my invention will be best and more fully understood from the following detailed description of a typical preferred form of the invention, throughout which description reference is had to the accompanying drawings, in which:

Fig. 1 is a front elevation of a typical davenport or day bed embodying my invention. Fig. 2 is an enlarged detailed view taken substantially as indicated by line 2—2 on Fig. 1 showing the parts in folded position. Fig. 3 is a view similar to Fig. 2 showing the construction partially operated. Fig. 4 is a view similar to Fig. 2 showing the construction fully operated or extended. Fig. 5 is a view taken as indicated by line 5—5 on Fig. 4, and Fig. 6 is an enlarged detailed

end view of the back construction showing it in the up position.

The construction provided by this invention is applicable, generally, to the folding bed type of davenport. I will confine the present disclosure to a form of the invention particularly suited to the ordinary or conventional folding bed davenport, it being understood that the broader features of the invention may be applied to various constructions of similar nature.

The construction includes, generally, a base 10, an inner frame 11 mounted for vertical movement in the base, a seat frame or outer bed frame 12, and means connecting the outer bed frame 12 with the base 10 and the inner frame 11 so that the outer frame is operable between a folded position where it is directly above the inner frame and an extended position where it adjoins the forward edge of the inner frame and is in the same horizontal plane as the inner frame. The construction also includes a back frame 13 mounted for vertical movement at the rear portion of the base. The construction includes other features such as means 14 operating to counterbalance the outer frame to make it easily operated, means 80 operating to counterbalance the back to make it easily operated, supporting legs 15 for the outer frame when in the extended position, means 16 for automatically operating the legs 14, etc.

The base 10 may be a rectangular structure having spaced ends joined by front and rear sides. In the construction shown each end of the base is in the form of a frame including legs 20 and horizontal braces 21 extending between the legs.

The inner bed frame 11 is a rectangular structure mounted in the base 10 for vertical movement between a down position such as is shown in Fig. 2 and an up position such as shown in Fig. 4. The frame 11 may be formed of angle iron, or the like, to have ends 24 and sides 25 extending between the ends. The frame 11 may be provided with a suitable spring construction 26 in the manner usual to devices of this character.

The seat frame or outer frame 12 may be similar, generally, to the inner frame, that is,

it may be a rectangular structure formed of angle iron, or the like, to have ends 27 and sides 28. The frame 12 may be provided with springs 29 or the like, similar to the 5 construction provided on the frame 11. The outer frame 12 is adapted to be operated between an in/or folded position, where it is above the inner frame 11, and an extended 10 position where it adjoins the forward side of the frame 11 and is in the same plane as the frame 11. When the outer frame 12 is in the folded position it is adapted to be used as a seat.

The means provided by this invention for 15 interconnecting the frame 11 and 12 includes, generally, a pair of links 35 at each end of the construction connecting the outer frame 12 with the base 10, and arms 36 projecting from the links 35 and carrying the inner 20 frame 11 so that the inner frame is moved vertically when the links are moved. The links 35 are all the same length and are arranged parallel with each other so that they remain in the same position or parallel with each 25 other throughout the operation of the mechanism. The links 35 at each end of the construction are spaced apart so that they operate to brace and lend rigidity to the construction. The upper ends of the links are pivot- 30 ally connected to the end 27 of the outer frame 12, while the lower ends of the links are pivotally connected to the brace 21 of the end of the base. The links are proportioned so that they allow the top frame 12 35 to be swung upward and forward and then downward and forward from the positions shown in Fig. 2, to the position shown in Fig. 4. It will be apparent that the links connect the top frame and base so that the 40 top frame is in the proper position with reference to the base and inner frame when in the two positions mentioned.

A pull or handle 60 may be provided on 45 the front side 28 of the upper frame 12. In practice the device 60 may be any form of hand grip mounted on the side 28 so that when the construction is in the folded position it is hidden from sight by ornamental facing on the base 10 and/or by upholstering 50 on the seat frame 12.

The arms 36 project from the lower end 55 portions of the links so that their outer ends engage the end 24 of the inner frame 11 as shown throughout the drawings. The arms 36 are proportioned and angularly disposed with reference to the links so that they operate to support the inner frame at the desired elevation when the construction is folded as 60 shown in Fig. 2 and move it upwardly into horizontal alignment with the outer frame upon the outer frame being moved to the extended position shown in Fig. 4. In practice I have found it practical to provide braces 37 between the outer portions of the arms and the links so that the arms and links are effec-

tively braced with reference to each other. The outer ends of the arms 36 are slidably connected with the parts 24 of the inner frame. I may provide pins 92 at the outer ends of the arms to operate in horizontal openings or slots 90 in the ends 24. Ties 91 connect the outer ends of the arms 36 so that the arms move simultaneously in the slots 90. In the drawings I have shown the pins 92 extending through the arms 36 the ties 91, the 70 braces 37, and slidably carried in the slots 90. The frame 11 mounted in this manner moves only a short distance horizontally during its movement between the in and the out 75 positions.

The horizontal movement of the frame 11 is governed by a connecting rod 100 having one end pivotally connected to the frame 11 and the other end pivotally connected with one of the links 35 at a point suitably spaced from the point of pivotal connection between the 80 said link and the base 10. With the construction just described the inner frame has the desired vertical movement accompanied by a short limited horizontal movement. This is 85 an important feature as it makes the construction compact.

The means provided for counterbalancing the construction so that it is easily operated 90 may include spring means connecting the movable parts and the base to be put under tension as the top frame 12 is lowered from its uppermost position to the folded position shown in Fig. 2 and when the outer frame is 95 lowered from its uppermost position to the in 100 position as shown in Fig. 4. The counterbalancing means may include two helical springs 38 at each end of the construction connecting the base 10 and a projecting part 39 on one of the links 35. In the preferred form of 105 the invention shown in the drawings, the springs 38 are connected to the part 39 and extend in opposite directions to connect to the two legs 20. In the construction illustrated the link 40 having the projection 39 110 is not centrally located between the legs 20. In such case the spring attached to the leg spaced farthest from the part 39 may be of heavier construction than the other. The springs 38 are proportioned so that one is 115 under tension when the frame 12 is positioned as shown in Fig. 2 while the other is under tension when the frame is positioned as shown in Fig. 4. With this arrangement the springs operate to counteract the weight of the bed 120 frames 11 and 12 and make the construction easy to operate.

The legs 15 are pivotally connected to the forward portion of the top frame 12 and are 125 in the nature of drop legs adapted to extend vertically between the frame 12 and the floor when the frame is extended as shown in Fig. 4, and to be folded up substantially parallel with the frame 12 when the construction is folded as shown in Fig. 2. The legs 15 may 130

be formed of pipe or tubing flattened at their upper ends to accommodate the pivotal connections with the frame.

The means 16 provided by my invention 5 operates to automatically move the legs 15 into operating position as the top frame is extended, thus assuring proper support for the outer frame when in the extended position. This means includes an arm extension 42 on 10 the forward link 35 at each end of the frame and connecting rods 43 extending between the arm extensions 42 and the legs, as clearly illustrated in Figs. 3 and 4 of the drawings. It will be apparent that operation of the links 35 causes movement of the arms 42 and that the 15 arms 42 in turn operate the connecting rods 43 so that the legs 15 are positively operated.

When the top frame is in the extended position its outer part is supported by legs 15 as above described, while its inner part may be supported by or connected with the inner frame 11 by the side 28 overlapping the side 25 of the frame 12 its entire length. The 20 frame 12 is somewhat shorter than the frame 11. The difference in the length of the frames 11 and 12 is sufficient to form the proper clearance between the ends 24 of the frame and the links 35 to permit the arms 36 and the braces 37 to operate freely. Projections 44 are provided on the ends 24 at points where they engage the inner sides of the overlapping portions of the ends 27 of the frame. The 25 projections 44 are provided to steady the construction when in the extended position, and so prevent lateral movement between the frames 11 and 12.

The back frame 13 is a rectangular structure mounted on an upwardly projecting extension 50 at the rear of the base and is movable between a down position such as is shown in Fig. 2, and an up position such as is shown in Fig. 3. The frame 13 may have ends 51 and sides extending between the ends. The 30 back frame 13 is shown provided with a suitable spring construction 52.

The means provided for mounting the back frame 13 for vertical movement includes, generally, a pair of links 54 at each end of the frame 13 connecting the frame 13 with the extension 50. The links 54 at each end of the back are spaced apart so that they operate to brace and lend rigidity to the structure.

The link 54 are proportioned so that they 35 allow the back frame 13 to be swung outwardly from the position shown in Fig. 2 to the position shown in Fig. 3. A rod 59 is provided to connect the two ends of the construction so that they will operate simultaneously.

The means 80 provided to counterbalance the back frame includes, a spring 70 at each 40 end of the back to assist in moving the back frame to the up position, and to hold it in such a position. Each spring has one end at-

tached to the extension 50 and the other end attached to one of the links 54 at a point between its ends. The points of connection of the spring 70 are located so that the spring is normally under tension and throws over or past the point of connection between the links and the extension 50 so that the spring operates to urge the back frame downwardly when the parts are in the position shown in Fig. 3 and upwardly when in the position shown in Fig. 4. It is preferred that the parts be related so that the spring throws over center after a short vertical movement from the position shown in Fig. 2.

The back frame 13 is normally supported 45 by the inner side of the upper frame 12. The bottom side of the back frame engages the top of the inner side 25 of the inner frame 12 and forms a continuous support for the back frame 13. The upper portions of the 50 sides 51 are provided with downwardly facing shoulders 101 which engage corresponding upwardly facing shoulders 102 on extension 50 when the back is in the down position.

When the bed construction is to be moved 55 from the folded position to the extended position, the outer frame is swung from the position shown in Fig. 2 to that shown in Fig. 4. During this operation the inner frame moves upwardly and forward. The upward 60 movement of the frame 11 lifts the back frame so that the springs 70 throw over center and carry the back frame to the up position shown in Figs. 3 and 4. When the bed construction is returned to the folded position the back 65 100 frame 13 may be readily lowered to its down position.

The operation of the device will be apparent from the foregoing detailed description. 70 It is also apparent that the construction provided by my invention is simple and inexpensive and is dependable and easy to operate.

Having described only a typical preferred form of my invention, I do not wish to limit 75 myself to the specific details set forth, but wish to reserve to myself any changes or variations that may appear to those skilled in the art or fall within the scope of the following claims.

Having described my invention, I claim:

1. A bed construction of the character described including, a base, an outer bed frame, links connecting the outer bed frame and the base, the outer bed frame being operable from 80 a position above the base to a position forward of the base, an inner bed frame normally disposed under the outer bed frame, the inner bed frame having horizontal slots, arms on the links slidably connected in the inner bed frame through the slots, the inner bed frame being operable vertically to a position adjacent the outer bed frame when the outer bed frame is in a position forward of the base, a control rod pivotally connecting the inner 85

- frame and a link, a tie connecting the outer portions of the arms, means counterbalancing the bed frames, the control rod being connected with the link at a point adjacent the connection of the link with the base and being connected to the inner frame at a point adjacent the inner end of the frame so that it aids in supporting the inner frame on the base when the frames are in the extended position.
- 10 2. A bed construction of the character described including, a base, an outer bed frame, spaced links pivotally connecting the outer bed frame with the base, the outer bed frame being operable from a position above the base to a position forward of the base, an inner bed frame normally spaced under the outer bed frame, like arms rigidly attached to the links and slidably connected with the inner bed frame, the inner bed frame being operable vertically to a position adjacent the outer bed frame when the outer bed frame is in the position forward of the base, a tie connecting the arms at the inner bed frame to maintain the arms in parallelism during operation and in corresponding positions relative to the inner bed frame, and a control rod pivotally connected to the inner frame at a point adjacent the inner end of the frame and pivotally connected with a link adjacent the pivotal connection of the link with the base so as to control the movement of the inner frame and aid in supporting the inner frame on the base when the inner frame is in the extended position.
- 15 35 In witness that I claim the foregoing I have hereunto subscribed my name.

WILLIAM AUGUST MOELLER.
